UNITED STATES PATENT OFFICE.

MARCUS DOERHOEFER, OF LOUISVILLE, KENTUCKY.

FEED-WATER REGULATOR.

SPECIFICATION forming part of Letters Patent No. 542,150, dated July 2, 1895.

Application filed March 4, 1895. Serial No. 540,470. (No model.)

To all whom it may concern:

Be it known that I, MARCUS DOERHOEFER, a citizen of the United States, and a resident of Louisville, in the county of Jefferson and State of Kentucky, have invented certain new and useful Improvements in Feed-Water Regulators; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a sectional view of the invention applied. Fig. 2 is a diagrammatic view of modification. Fig. 3 is a fragmental sectional view illustrating change in regulator for modification.

The object of this invention is to provide means of simple and reliable character for regulating the supply of water to tanks or reservoirs of different kinds, and especially to the feed-water-heating tanks or reservoirs of steam-boilers and to those tanks or reservoirs which supply water to other tanks which may be situated at the tops of buildings for the purpose of supplying water to the same and into which the water is forced by the action of a pump from the tank or reservoir below.

When the regulator is applied to a feed-water-heating tank, it is designed to automatically govern the supply of water thereto to maintain a very nearly constant level therein, whatever may be the demand made upon such tank by the engine-pumps.

When applied to the other purpose above referred to, the regulator acts automatically to prevent the overflow of the lower tank or reservoir, and to maintain a nearly constant level therein by setting in operation the pump which forces the water to the upper tank, whereby such upper tank is kept supplied by receiving the surplus water from the lower tank.

I will first describe the arrangement and operation of the invention as applied to a feed-water-heating tank and as illustrated in

Fig. 1. In the drawings, the letter A designates a closed water and steam tight chamber in which is placed a float B, which preferably consists of a hollow copper body or ball having at its lower portion a stem a, which works in a suitable guide b at the lower portion of said chamber. C designates a smaller chamber, which is offset from the upper portion of the chamber A, with which it communicates through a large opening c in the wall of the latter. D designates the shell or casting of said chamber C, which is attached to the shell of the chamber A in such a manner that it can be removed therefrom. At its outer end said shell D is formed with a valve-seat portion F. F² is a chambered cap, which is secured to the outer end of said shell and within the chamber of which is a slide-valve F', which seats upon the outer face of said seat portion. G is a lever, which is pivotally connected with the float at g and which extends into the chamber C, near the outer extremity of which it is fulcrumed at g'. The extremity of the lever is loosely connected to the valve F, usually by forming on the lever a ball end f, which rolls in a socket f' of the valve and permits the latter a true movement on its seat. This connection is made through an opening in the seat portion F, which opening is closed by the valve in all positions of the latter. H indicates a feed-water-heating tank, which is connected with the float vessel or chamber A by means of a pipe I, and with the valve-seat F by means of a second pipe J and port K, which opens into the valve-chamber D' through the valve-seat. K' is a gage, by means of which the water-level in the float-vessel and in the tank H is indicated, the pipe I causing the same level to be maintained in both vessels.

The operation is as follows: When the tank H is filled, the float is raised to the position shown in Fig. 1, and the valve closes the port K, thereby shutting off all supply of water to said tank through the port K and pipe J. As the water falls in said tank the float also falls, and through the lever G moves the valve to uncover to a greater or less extent the port K and again admit water to said tank. It

will be readily understood without further description that a nearly-constant level of water will always be maintained in the tank, whether the feed-pump be running fast or slow.

I will now proceed to describe the second application of the invention above referred to and illustrated in Figs. 2 and 3 of the drawings. L designates a large tank or reservoir, which is supplied with water from the wells L' and pumps L² or other source through pipe L³. M designates a second tank, which is supposedly situated at the top of a building to which it supplies water, receiving its supply from the tank L through a pipe M' and pump M². N is an overflow-pipe for the tank M. P designates the regulator, which is in all respects constructed the same as above described, with the exception that the port K and pipe J communicate with the upper portion of the shell or casting D and valve chamber D', instead of with the lower portion. For this purpose the pipe E acts as a steam-pipe which is connected to a steam-boiler, (not shown,) while the pipe J leads to the steam-chest of the pump M². The pipe I is connected to the tank L, as before.

The operation is as follows: When the tank L fills, the float is raised in the chamber A, and the port K (which has been closed) is by the movement of the valve F' opened. Steam is now admitted into the pipe J to the pump M², which is thereby set in operation to force water to the upper tank M. When the water falls in the tank L, the port K is again closed and the pump M² stops.

It will be seen that in the arrangement shown in Fig. 1 the valve operates with a low level of water in the chamber A, while in the arrangement shown in Fig. 3 it operates with a high level. In order to adapt the regulator to either of these actions, it is only necessary to attach the shell D to the shell of the main chamber in proper position, so that

an ordinary mechanic can quickly convert the device from one arrangement to the other.

Having thus described my invention, what I claim as new, and desire to secure by Letters Patent, is—

1. In a regulator for feed water heating and other tanks, the combination of a float chamber, a smaller chamber offset from the float chamber, the shell of said smaller chamber having a valve seat portion at its outer end, a chambered cap secured to said shell over said valve seat, a slide valve seated within the chamber of said cap, and seating against the outer face of said seat portion, an inlet to and an outlet from the chamber of said cap, the outlet port being controlled by the said valve, and a float-actuated lever connected to said valve through an opening in said seat portion, substantially as specified.

2. In a regulating device for feed water or other tanks, the combination of a float vessel A, a shell D attached to the upper portion of said vessel and having a chamber which communicates with the chamber of said vessel, said shell having a valve seat portion at its outer end, a chambered cap-piece secured to the outer end of said shell over said seat portion, a slide valve within the chamber of said cap and seating upon the outer face of said seat portion, an inlet leading into said chamber, an outlet leading therefrom through said seat portion, and a float-actuated lever extending through the chamber of the shell D, within which it is fulcrumed, and connected to said valve through an opening in said seat portion which is closed by said valve, said shell D being capable of reversal, substantially as and for the purposes specified.

In testimony whereof I affix my signature in presence of two witnesses.

MARCUS DOERHOFER.
